CORRECTIVE DEVICE FOR SECONDARY CLOCKS

Adolph L. Denniston, Chicago, Ill., assignor, by
mesne assignments, to Stromberg Electric Com-
pany, a corporation of Delaware

Application August 29, 1925, Serial No. 53,231
Renewed August 23, 1934

14 Claims.

(Cl. 58—24)

My invention relates to corrective devices to correct the time of any secondary apparatus controlled by a master clock in the event that the time of any secondary apparatus is out of synchronization with the master clock due to temporary interruptions in the current supply or for other reasons.

One of the objects of my invention is to provide a corrective device which can be used in connection with the usual two-wire relay circuit.

A further object of my invention is to provide a corrective device which can be readily combined with existing types of mechanisms.

A further object is to provide a corrective device having provisions for correcting a plurality of secondary devices individually without the use of electrical contacts in the secondary devices.

Further objects will appear from the description and claims.

20 In the drawing, the figure shows diagrammatically parts of the secondary and master clock with the relay, corrective device, and wiring arrangements.

Referring to the drawing in detail, the parts of 25 the secondary clock shown comprises a secondary impulse electromagnet 1 in the relay circuit, an armature 2 controlled by this electromagnet, a lever 3 on which this armature is mounted, a pawl 4 pivoted to the upper end of this lever 3, and a 30 ratchet 5 actuated by this pawl.

The relay shown comprises an electromagnet 6 in the master clock contact circuit, and a switch 7 controlled by this electromagnet and controlling the relay circuit through the secondary impulse magnet. The master clock mechanism shown comprises merely a time-controlled periodic contact device 8 which is ordinarily controlled by the master clock in such a way as to close the circuit through the relay magnet once per minute.

40 The corrective device shown comprises a high frequency switch 9 for advancing such secondary clocks as may have gotten behind the master clock, a cam member 10 mounted on a shaft 11 driven by the master clock for periodically placing the high frequency switch 9 in parallel with the low frequency switch 8 to control the relay magnet circuit, a pivoted arm 12 for periodically rendering ineffective the secondary clock pawls 4 of such secondary clocks as may have gotten 45 ahead of the master clock, a polarized relay 13 in the relay circuit for controlling this lever 12, a pole-changing or current-reversing device 14 for periodically reversing the relay circuit connections and a cam 15 mounted on the master clock-driven cam shaft 11 for periodically energizing the electro-magnet 16 of the pole-changing device for causing reversal of the relay circuit magnets.

When the electro-magnet 16 is not energized the armatures 16a are not attracted and remain in the position shown in the drawing, in which the line 16b is connected with the battery through the contact 16c and the lead 18 and the line 16d is connected with the battery through the contact 16e and the lead 16f.

When, however, the electro-magnet 16 is energized the armatures 16a are attracted and engage the contacts 16g and 16h respectively so that the line 16b is then connected with the battery through the contact 16g and lead 16f, and the line 16d is connected with the battery through the contact 16h and lead 18.

The cam 15 which controls the reversal of current in the relay circuit may be timed so that the circuit from the battery 17 through the conductors 18 and 19, contacts 20 and 21, conductor 22, magnet 16, and conductor 23 is closed from 55 minutes and 10 seconds after the hour to 59 minutes and 50 seconds after the hour. The cam 10 which controls the placing of the high frequency switch 9 in parallel with the low frequency switch 8 may be timed so that the contacts 24 and 25 will be in engagement with each other from 59 minutes and 15 seconds past the hour to 59 minutes and 45 seconds after the hour. The high frequency switch is so controlled by the master clock that the contacts make and break the circuit every two seconds so that during the thirty seconds in which the high frequency switch is in parallel with the low frequency switch it will cause 15 impulses to pass through the relay magnet 6, the circuit being through the conductors 18, 19 and 26, contacts 24 and 25, high frequency switch 9, conductor 27, magnet 6 and conductors 28 and 23, back to the battery.

When the current which flows through the coil of the polarized relay 13 is in one direction, the action of the electro-magnet is such as to tend to raise the lever 12 which is pivoted at 29. When a current through the polarized relay is in the opposite direction, the action is such as to tend to lower the lever. This polarized relay, as is the case with all polarized relays of the type shown, comprises a permanently magnetized member, in this case movable with the lever 12, the tendency of which is to move in one direction when the current flow through the coil of the relay is in one direction and the tendency of which is to move in the opposite direction when the flow through the relay coil is reversed. The 55

shaft 30 on which the ratchet wheel on the secondary clock is mounted, has mounted thereon a disk 31 having a notch 32 therein for cooperation with a pin 33 on the lever 12. This notch is so positioned that if the secondary clock is in synchronism with the master clock, the notch will come opposite the pin on the lever at 59 minutes after the hour. During the period from 5 55 minutes and 10 seconds past the hour to 59 10 minutes and 50 seconds after the hour (by master 15 clock time) when the contacts 20 and 21 are held in engagement with each other by the cam 15, the impulses through the polarized magnet 13 are such as to tend to raise the lever 12 and bring the 20 pin 33 into engagement with the disk 31. If, however, the secondary clock is not fast, the pin 33 will simply engage the circular edge of the disk 31 and will not prevent movement of the ratchet 5 under the action of the pawl 4. If, however, 25 any one of the secondary clocks is a few minutes fast, the notch 32 in the disk will be brought opposite the pin 33 on the lever some time before the end of the hour, (by master clock time) and the energization of the polarized magnet 13 will 30 raise the lever and bring the pin 33 into the notch 32, allowing the lever to rise higher than when the pin on the lever simply engaged the circular edge of the disk. This excess movement of the lever brings the pin 34 on the end of the lever 35 behind the downwardly extending projection 35 on the pawl 4, and renders this pawl ineffective to engage the teeth of the ratchet 5 in the oscillatory movement of the lever 3 on which the armature 2 is mounted. This armature lever is 40 pivoted at 36 and a tension spring 37 is provided tending to hold the armature 2 away from the electro-magnet. When the lever 12 controlled by the polarized magnet is in its uppermost position with the pin 33 entering the notch 45 32 on the disk, and secondary impulse magnet is energized to draw the armature toward it, the lower end of the extension 35 on the pawl 4 strikes against the pin 34 on the lever 3 and throws the point 38 of the pawl away from the teeth 39 of the ratchet wheel, so that oscillation of the pawl-carrying lever 3 has no effect on the ratchet wheel. Any secondary clocks which have gotten 50 ahead of the master clock will thus be held at one minute of the hour so long as the contacts 20 and 21 are in engagement with each other. However, just 10 seconds before the end of the hour (by master clock time) the contacts 20 and 21 are separated so that the next impulse through the coil of the polarized relay 13 will be in a direction 55 to lower the lever 12 and permit the pawl 4 to become effective again. Any secondary clocks which may have gotten ahead of the master clock are thus held at one minute of the hour (by master clock time) until 10 seconds before the 60 end of the hour, so that the next impulse through the secondary impulse magnet will bring them to the even hour in synchronism with the master clock.

In the event that any of the secondary clocks 65 may have gotten a few minutes slow, as compared with the master clock, they are automatically stepped up just before the end of the hour by means of the high frequency contact device 9. This high frequency contact device is placed in 70 parallel with the minute contact device at 45 seconds before the end of the hour and remains thus until 15 seconds before the end of the hour. During these 30 seconds it causes 15 impulses to go through the coil of the relay magnet 6 and 75 this causes 15 impulses to pass through the coil

of the secondary impulse magnet 1. This causes 15 rapid oscillations of the pawl-carrying levers 3 of the secondary clocks, and brings any of them which may be a few minutes slow, up into synchronism with the master clock. If one of these 5 slow secondary clocks is only a few minutes slow (for instance, three minutes) the first three rapid oscillations of the pawl-carrying lever 3 will bring the secondary clock into synchronism with the master clock and the remaining 12 rapid oscillations of the pawl-carrying lever will be wasted so far as any movement of the ratchet wheel is concerned, as the pin 33 on the lever controlled by the polarized magnet will drop into the notch 32 on the disk when the secondary clock shows 15 one minute of the hour, and the pin 34 on the lever will render the ratchet actuating pawl 4 ineffective to actuate the ratchet during the remaining 12 oscillations of the pawl-carrying lever.

In the claims where I have used the expression 20 "secondary clock" it will be understood as including broadly secondary clock mechanism, such as time controlled workmen's time recorders, etc.

Having thus described my invention, what I 25 claim as new and desire to secure by Letters Patent of the United States is:

1. A secondary clock comprising an impulse magnet for controlling the secondary clock movement, a relay and relay circuit in which said secondary impulse magnet is connected, a master 30 clock comprising a time-controlled contact device for normally controlling the relay to control the secondary magnet, and a corrective device comprising a high frequency time controlled contact device for occasionally controlling the 35 relay to advance any secondary apparatus which may be slow as compared with the master clock, master clock controlled means for periodically rendering the high frequency switch effective to control the relay, a polarized magnet in the relay 40 circuit, master clock controlled means for periodically reversing the relay circuit connections and thus reversing the connections for the polarized magnet independently of the time of the secondary clock, and means controlled by the time 45 of the secondary clock and also by energization of said polarized magnet during the sending of the high frequency impulses for rendering the secondary impulse magnet ineffective to advance the secondary clock mechanism in the event that 50 the secondary clock is fast, said last means comprising a member controlled by the polarized magnet and by the secondary clock, which tends to move in one direction for one direction of current flow in the relay circuit and in another direction upon a reversal of this current flow, and means for preventing movement of said member in one direction unless the secondary clock is 55 fast.

2. A secondary clock comprising an impulse 60 magnet for controlling the secondary clock movement, a relay and relay circuit in which said secondary impulse magnet is connected, a master clock comprising a time-controlled contact device 65 for normally controlling the relay to control the secondary magnet, and a corrective device comprising a high frequency time controlled contact device for occasionally controlling the relay to advance any secondary apparatus which may be slow as compared with the master clock, master 70 clock controlled means for periodically rendering the high frequency switch effective to control the relay, a polarized magnet in the relay circuit, master clock controlled means for periodically reversing the relay circuit connections and 75

thus reversing the connections for the polarized magnet independently of the time of the secondary clock, and means controlled by the time of the secondary clock and also by energization of said polarized magnet during the sending of the high frequency impulses for rendering the secondary impulse magnet ineffective to advance the secondary clock mechanism in the event that the secondary clock is fast, said last means comprising a member controlled by the polarized magnet and by the secondary clock, which tends to move in one direction for one direction of current flow in the relay circuit and in another direction upon a reversal of this current flow, and means for preventing movement of said member in one direction unless the secondary clock is fast, said secondary clock comprising a ratchet and a pawl for driving said ratchet driven by said impulse magnet, said member engaging said pawl to render it ineffective to operate said ratchet if the secondary clock is fast.

3. A secondary clock for use in synchronized clock systems and comprising a non-polarized impulse magnet which by its own action effects all advancing movements of the clock which are required for normal step-by-step advance or for accelerating the clock if the same is slow, and a ratchet actuated by said impulse magnet, with means at each secondary clock, including a polarized magnet controlled by master clock apparatus for suspending the advance of said secondary clock and rendering said impulse magnet ineffective to cause force to be exerted on said ratchet under certain chronological conditions of the clock and permitting a reinitiated advance of the clock under the action of the impulse magnet after its action has been suspended, and means including a single line circuit extending into the clock from the master clock for sending thereto from the master clock both the normal and fast impulses which normally advance and accelerate the clock and for also transmitting thereto current of special characteristics which upon its reception by the clock is adapted to reinitiate an advance thereof after its operation has been suspended.

4. In a secondary apparatus for use in a time-controlled system, an impulse magnet, an actuating member controlled thereby, a ratchet wheel operated by said member to periodically advance said apparatus under control of said impulse magnet, a second magnet in circuit with said impulse magnet and concurrently energized therewith, and means controlled by said second magnet and operated only when said apparatus is in a particular predetermined chronological position for mechanically preventing effective engagement of said actuating member with said ratchet wheel, thereby preventing advance of said apparatus.

5. In a secondary apparatus for use in a time-controlled system, an impulse magnet, an actuating member controlled thereby, a ratchet wheel operated by said member to periodically advance said apparatus under control of said impulse magnet, a second magnet in circuit with said impulse magnet and concurrently energized therewith, and means controlled by said second magnet and operative only when said apparatus is in a particular predetermined chronological position for mechanically preventing effective engagement of said actuating member with said ratchet wheel and for holding said ratchet wheel against movement, thereby preventing advance of said apparatus.

6. In a secondary apparatus for use in a time-controlled system, an impulse magnet, a ratchet and pawl controlled by said impulse magnet to effect all advancing movement of said apparatus, means for holding said ratchet to prevent movement of said apparatus, and means for preventing said pawl from exerting driving force on said ratchet by the energization of said impulse magnet while said holding means are effective.

7. In a secondary apparatus for use in a time-controlled system, an impulse magnet, a ratchet and pawl controlled by said impulse magnet to effect all advancing movement of said apparatus, a second magnet, and means controlled by said second magnet and operative only when said apparatus is in a particular chronological position for preventing movement of said ratchet and for mechanically preventing said pawl from exerting driving force on said ratchet when said impulse magnet is energized.

8. In a secondary apparatus for use in a time-controlled system, an impulse magnet having an armature and pawl, a ratchet wheel normally engaged by said pawl, and means operative only when said apparatus is in a particular chronological position for mechanically disengaging said pawl from said ratchet wheel when said armature is displaced by the energization of said magnet and thereby preventing actuation of said ratchet wheel.

9. A secondary clock for use in a synchronized clock system of the impulse type wherein each secondary impulse clock is advanced by regularly recurring impulses and accelerated if slow by more rapidly recurring current impulses comprising an electromagnetic actuating device, a ratchet actuated by said electromagnetic device, means controlled by the chronological condition of the secondary clock for rendering said electromagnetic device ineffective to cause a driving force to be exerted on said ratchet and controlled by a reversal of current for rendering said electromagnetic device effective to cause force to be exerted on said ratchet.

10. A secondary clock for use in a synchronized clock system of the impulse type wherein each secondary impulse clock is advanced by regularly recurring impulses in one certain direction and accelerated if slow by more rapidly recurring current impulses comprising an electromagnetic actuating device, a ratchet actuated by said electromagnetic device, means controlled by the chronological condition of the secondary clock for rendering said electromagnetic device ineffective to cause a driving force to be exerted on said ratchet and controlled by a reversal of current for rendering said electromagnetic device effective under impulses in said one certain direction to cause force to be exerted on said ratchet.

11. In a secondary apparatus for use in a time controlled system, an impulse magnet having an armature and pawl, a ratchet wheel normally engaged by said pawl, and means dependent upon the chronological condition of said apparatus for preventing effective engagement of said pawl with said ratchet wheel when said magnet is energized, thereby preventing advance of said ratchet wheel.

12. In a secondary apparatus for use in a time controlled system, an impulse magnet having an operating pawl, a ratchet wheel engaged by said pawl to advance said apparatus under control of impulses received by said magnet, and means dependent upon the chronological position of said secondary apparatus for preventing said

pawl from exerting driving force on said ratchet under continued reception of impulses by said magnet.

13. In a time controlled system in which a master apparatus transmits operating and synchronizing impulses over a common circuit to secondary apparatus, an impulse magnet in said secondary apparatus connected to said line circuit to receive all of said impulses, an operating pawl and a ratchet wheel controlled by said magnet to advance said secondary apparatus, and means operative only when said secondary apparatus is in a predetermined chronological position for preventing said pawl from exerting driving force 10 on said ratchet.

14. In a secondary apparatus for use in a time-controlled system, an impulse magnet, an actuating member controlled thereby to effect all advancing movements of said apparatus, a second magnet associated with said impulse magnet and 5 concurrently energized therewith, means controlled by said second magnet for blocking said actuating member so that the energization of said impulse magnet is ineffective, and means for preventing the operation of said last means upon 10 each energization of said magnet until said apparatus reaches a particular predetermined chronological position.

A. L. DENNISTON. 15
